UNITED STATES PATENT OFFICE.

STEPHEN T. STUVER, OF BELLINGHAM, WASHINGTON.

DESIGN FOR A PICTURE FRAME OR BASE.

No. 37,600.

Specification for Design.

Patented Oct. 31, 1905.

Application filed July 27, 1905. Serial No. 271,549. Term of patent 7 years.

To all whom it may concern:

Be it known that I, STEPHEN T. STUVER, a citizen of the United States, residing at Bellingham, in the county of Whatcom and State of Washington, have invented a new, original, and ornamental Design for a Picture Frame or Base, of which the following is a specification, reference being had to the accompanying drawings, forming a part thereof, in which—

Figure 1 is a front view, and Fig. 2 an edge view, thereof.

I claim—

The ornamental design for a picture frame or base as shown.

STEPHEN T. STUVER. [L. S.]
